The diagram illustrates a cross-sectional view of a device assembly. At the top, a horizontal bar is secured by a fastener 9. A tube 8 is attached to the bar, and a tube 7 is attached to the tube 8. A tube 5 is attached to the tube 7. A rectangular frame 42 contains a circular component 35. A tube 36 extends from the frame 42. A tube 61 is attached to the bottom of the frame 42. A tube 6 is attached to the bottom of the frame 42. A tube 62 is attached to the right side of the frame 42.

LADY'S HANDBAG OR POCKETBOOK

Antonio Souza, Cambridge, Mass.

Application January 26, 1940, Serial No. 315,831

3 Claims. (Cl. 206—41.3)

This invention relates to ladies' handbags or pocketbooks and the primary object of this invention is the provision of a device of this character which will be extremely compact and durable and will provide adequate accommodation for various types of cosmetics and accessories therefor and will provide accommodation for note paper and writing accessories and a combined cigarette case and lighter conveniently operated from the exterior of the device so that a cigarette may be easily obtained and lighted when desired and an efficient electric illuminating means as well as ample space for wearing apparel such as gloves, handkerchiefs and the like.

With these and other objects in view, the invention consists in certain novel features of construction, combination and arrangement of parts to be hereinafter more fully described and claimed.

For a complete understanding of my invention, reference is to be had to the following description and accompanying drawings, in which

Figure 1 is a perspective view illustrating a lady's handbag or pocketbook constructed in accordance with my invention and showing one side thereof fully open.

Figure 2 is a perspective view illustrating the pocketbook or handbag and showing the opposite side thereof open.

Figure 3 is a side elevation showing the device in a closed position.

Figures 4 is a fragmentary vertical sectional view illustrating the combined cigarette case and lighter and cigarette ejecting means located in the device and operable from the exterior thereof.

Referring in detail to the drawings, the numeral 5 indicates an elongated rigid case, the lower or bottom wall of which is rounded, as shown at 6, and the top wall flat and equipped with strap fasteners 7 to which a strap-type handle 8 is connected. An adjusting fastener 9 is provided on the strap-type handle whereby the latter can be tensioned or slackened as desired.

Arranged between the side walls of the case and upon the interior thereof is a dividing partition 10 extending longitudinally and for the full length of the case. Upon one side of the partition is arranged a series of partitions 11 for dividing the case upon one side of the partition 10 into an intermediate compartment 12 and end compartments 13 and 14. One side of the case is formed by doors 15, 16 and 17. The doors 16 and 17 are for closing the end compartments 13 and 14 while the door 15 is for closing the interme-

diate compartment 12. The doors are hingedly mounted and are held in a closed position by spring catches 18. When viewing the device as shown in Figure 1 the door 16 swings to the right when assuming an open position and the door 17 swings to the left when assuming an open position while the door 15 swings downwardly when assuming an open position.

The door 17 has secured upon its inner face a writing instrument rack 19. Also secured on the inner face of the door is a writing pad 20 as well as a calendar 21.

Arranged in the compartment 14 are drawers 22 and 23 in which various articles may be placed and if desired the drawer 23 may be secured by a key operated lock.

The door 15 has secured upon the inner face thereof and covering a portion of said door a mirror 24 and also mounted upon the inner face of the door 15 is a series of racks 25 for the accommodation of various kinds of cosmetics. It is to be noted that the racks 25 move with the door 15 and when the latter is in an open position the case may be laid upon one side thereof so that the door 15 assumes a vertical position with the handle 8 towards the user. Thus the user may obtain a clear view in the mirror as well as obtain the various cosmetics from the racks in the make-up or beautifying of the face.

The rounded bottom wall 6 will permit the case to be readily tilted over onto either of its sides when placed on a table or like support.

Suitably mounted within the compartment 13 is a combined mechanical cigarette lighter and case 26. The combined mechanical cigarette lighter and cigarette case 26 is best shown in Figure 4 and it is to be noted that it consists of a casing 27 including a cigarette compartment 28 and a lighter fluid compartment 29. The casing 27 is removably mounted in the case 5 and is provided with a neck 30 connecting with an opening 31 provided in one of the end walls of the case for the purpose of permitting the lowermost cigarettes within the compartment to be moved out of the case 5 for use through the operation of an ejector 32.

The ejector 32 consists primarily in a slidable member 33 on which the lowermost cigarette may come to rest in the compartment 28 and has an upturned end 34 so as to engage with one end of the lowermost cigarette so that when the member 33 is slid in the direction of the opening 31 and through the latter the lowermost cigarette will be moved substantially fully outwardly of the case 5.

An operating rod 35 is slidably mounted in an opening provided in the case and is connected to the slideable member 33, as shown at 36. The portion 36 operates between a pair of spring members 37 for limiting the sliding movement of the member 33 by the operating rod 35 in opposite directions.

The mechanical lighter mechanism is indicated generally by the character 38 and is of a conventional construction the details of which are omitted in the present showing of the invention. The mechanism 38 includes the usual pivotally mounted cap 39 for covering the wick and other mechanism and is pivotally mounted, as shown at 40, and carries on its pivoted end an arm or extension 41 to which is connected a flexible element 42. The flexible element extends through an opening provided in one end wall of the case 5 so that the cap 39 may be swung upwardly for the actuation or ignition of the lighter, it being understood that the cap 39, as in the majority of mechanical lighters, is of the self-closing type, so that when the flexible element is manually released the cap 39 assumes a closed position.

A trap door 43 is provided in the top wall directly above the lighter mechanism and is connected to the cap 39 by a link 44, the latter having pivotal connection both with the trap door and the cap. When the cap 39 moves into an uncovering position or for actuating the ignition means the trap door 43 is opened so that the flame may extend outwardly of the case 5 for lighting a cigarette. The door 16 which closes the compartment 13 and in which the combined cigarette case and lighter is located is provided with ventilating openings 45 so as to allow sufficient air to support the burning of the lighter.

The case 27 is provided with a door 46 of the hinged type so that the compartment 28 may be opened and closed for the purpose of permitting a person to fill the compartment 28 with cigarettes when necessary. The filling of the lighter fluid chamber 29 can be accomplished by the removal of a plug 47.

In the foregoing description I have set forth what is located upon one side of the partition 10 within the case 5 and located in the case 5 upon the opposite side of the partition 10 are compartments 48 and 49 extending the full length of the case and separated from each other by a partition 50. The compartments are closed by a fabric or some other similar material covering 60 in which are formed entrances to said compartments closed by Zipper type fasteners 61.

While I have described one side of the case 5 as being closed and opened by the doors 15, 16 and 17, the other side of the case is in the form of a single door 62 held in a closed position by a suitable catch 63. It is to be noted from Figure 2 that this door swings downwardly to assume an open position and completely exposes the Zipper type fasteners so that the covering 60 can be opened to give access to the compartments 48 and 49. These compartments are of comparatively large size to accommodate wearing apparel, such as gloves, handkerchiefs or the like or any other articles may be stored therein in accordance with the desires of the user.

One of the end walls of the case 5 has an opening in which is mounted the lens 64 of a con-

ventional flashlight, the latter being confined in the lower part of the case 5 provided by the rounded bottom wall 6 and the lighting and extinguishing thereof can be carried out through the operation of a finger piece 65 extending through the case 5, as shown in Figure 1.

From the foregoing description taken in connection with the accompanying drawings it will be seen that a very convenient handbag or pocketbook has been provided for use by ladies and will accommodate all of the toilet articles that are needed by a lady while away from home as well as accommodating cigarettes and making provision for the lighting of cigarettes and further accommodating writing material and accessories as well as providing comparatively large storage spaces for wearing apparel such as handkerchiefs, gloves and the like.

While the present device is designed for the accommodation of so many articles its construction is such that it is compact, easy to carry and handle and may be manufactured and sold at a low cost.

It is believed that the foregoing description, when taken in connection with the drawings, will fully set forth the construction and advantages of this invention to those skilled in the art to which such a device relates, so that further detailed description will not be required.

Having thus described the invention, what I claim is:

1. In a device of the class described a case having an opening in its top and a hole in one end thereof adjacent the top, a door for closing the opening, a lighter in the case including a neck positioned directly below the opening, a hinged cover for closing the upper end of the neck, a flexible member connected with the cover and passing through the hole for opening the cover and a link connecting the cover to the door for simultaneously opening the door with the cover by a pull on the flexible member, simultaneous opening of the door and cover permitting flame from the lighter to extend outwardly of the case to provide for lighting a cigarette.

2. In a device of the class described, a case having a hole in one end thereof, a cigarette container located in the case and having a neck of tubular form extending from one side edge thereof at the bottom thereof and in communication with the hole, the bottom of the container being slidably supported and having one end thereof adapted to be passed through the hole to eject a cigarette through the hole and a rod connected with the bottom and passing through said end of the case below the hole therein for reciprocating said bottom.

3. In a device of the class described, a case, a cigarette lighter in the upper portion of the case and including a neck, a cover for the neck, a door covered opening in the top of the case directly above the neck, a flexible member connected with the cover and passing through the hole in the case for opening the cover, and means for opening the door simultaneously with opening of the cover to permit the flame from the lighter to extend out of the case and thereby provide for lighting of a cigarette.

ANTONIO SOUZA.
